WASHING MACHINE

Arthur H. Labisky, Barton, Wis., assignor to The
Barton Corporation, West Bend, Wis., a corpora-
tion of Wisconsin

Application July 13, 1935, Serial No. 31,156

4 Claims. (Cl. 68—4)

This invention relates to washing machines for cleansing clothing and the like.

While the washing action of most washing machines is such that articles of clothing and the like are not damaged thereby, it has been found that light and delicate articles are sometimes torn or damaged, particularly if washed along with heavier articles of clothing, and the primary object of my invention is to wash light and delicate articles of clothing and the like simultaneously with the washing of other articles without damage to the light and delicate articles and the like, and an ancillary object is to enable light and delicate articles of clothing and the like to be washed separately from but simultaneously with and in the same liquid as other articles of clothing.

Other objects are to provide a compartment in a washing machine tub in communication with the liquid in the tub and in which light and delicate articles may be washed separately from articles in the tub proper; and to impart an effective cleansing movement to water admitted into the compartment.

Washing machines usually have an agitator or similar means for imparting movement to the saponified water or other liquid in the tub of the machines to effect cleansing of articles of clothing and the like in the tub, and a further object of my invention is to provide an agitator which will impart an effective cleansing movement to the liquid in a washing machine tub.

Still further objects are to utilize the oscillatory or other movement imparted to the agitator in a washing machine tub to impart the cleansing action to water admitted into a compartment in the tub in which light and delicate articles may be washed separately from articles in the tub proper; to provide a member which may be mounted in a washing machine tub to provide a compartment in the tub separated from the rest of the tub; to so mount the member in the tub that it may be removed therefrom when so desired; to provide means on the agitator in a washing machine tub to which a member providing a separate compartment may be attached and to utilize such means to impart a cleansing movement to liquid in the tub when such a member is not connected thereto; to provide means in a member providing a separate compartment in a washing machine tub to impart a cleansing movement to liquid admitted into the separate compartment and to also use such means to connect the member to an operative part in the tub; to provide cooperating parts on the agitator in a washing machine tub and a member providing a separate compartment in the tub which will interconnect the agitator and member and support the member in operative position in the tub; and to provide a washing machine in which light

and delicate articles may be optionally washed separately from but simultaneously with other articles and which will be of simple and economical construction and efficient and positive operation.

Selected embodiments of my invention are illustrated in the accompanying drawing wherein—

Fig. 1 is a fragmentary vertical sectional view of a washing machine embodying one form of my invention;

Fig. 2 is a transverse sectional detail view taken substantially on the line 2—2 on Fig. 1;

Fig. 3 is a perspective view of a member, a portion of which is broken away, which provides a compartment separate from the tub proper of a washing machine when mounted in such a tub;

Fig. 4 is a perspective view of the agitator shown in Fig. 1;

Fig. 5 is an elevational side view, in which certain parts are broken away, of another form of my invention; and

Fig. 6 is a transverse detail view taken substantially on the line 6—6 on Fig. 5.

In the accompanying drawing I have shown a washing machine tub 7 supported by a suitable fragmentally illustrated frame 8 on which suitable means for imparting an oscillatory or other movement to the vertical shaft 9 may be mounted, one end of the shaft 9 being suitably connected to such means which include an electric motor or other source of power. Suitable means of this kind are illustrated and described in my Patent 1,929,747, patented October 10, 1933, but it is to be understood that any suitable means may be used without departing from the purview of this invention.

The shaft 9 extends through an opening 10 in the bottom of the tub and through a bore in the standard 11 which extends upwardly in the tub at the center thereof. A flange 12 on the standard 11 rests on a gasket 13. When a nut 14 or the like is engaged with the screw-threaded portion 15 of the standard extended through the opening 10, the gasket 13 is clamped against the bottom of the tub and prevents leakage through the opening 10. A bearing 16 is provided on the periphery of the standard 11 at the upper end thereof and a flange 17 on the standard extends beyond this bearing at the lower end thereof. A bearing collar 18 is provided on the standard about midway between the flanges 12 and 17. The shaft 9 has a polygonal portion 19 on the upper end thereof which extends above the bearing 16.

In Fig. 1, I have shown an agitator 20 including a sleeve 21 having a bore 22 at the upper end thereof adapted to embrace the bearing 16. The inner opening in the sleeve is enlarged at the lower end of the bore to provide a shoulder 23 that is adapted to rest on the upper surface of the

flange 17. The lower end of the sleeve 21 is flared outwardly as indicated at 24 and the inner opening in the sleeve is shouldered, as indicated at 25, to provide a bore 26 adapted to embrace the collar 18. When the shoulder 23 engages the flange 17, the lower end of the agitator 20 is supported slightly above the bottom of the tub 7 and the cooperation of the bore 22 with the bearing 16 and the bore 26 with the collar 18 guides the agitator in its movement in the tub to prevent wobbling or other undesired movement thereof.

A thimble 27 is provided at the top of the sleeve 21 and includes a polygonal socket complementary to the polygonal portion 19 which is embraced in this socket. Diametrically opposed recesses 28 are provided in the upper end of the sleeve 21 and similarly located ears 29 depend from the lower end of the thimble 27. When the ears 29 are seated in the recesses 27, the agitator 20 is connected to the shaft 9 and in those instances in which an oscillatory movement is imparted to the shaft 9 a similar movement is imparted to the agitator 20. When, however, the ears 29 are retracted from the recesses 27 and are seated on the upper end of the sleeve 21, the agitator is disconnected from the shaft 9 and the shaft may operate freely without imparting any movement to the agitator 20. A handle 30 is provided on the thimble 27 to facilitate insertion and retraction of the ears 29. A retaining band 31 is fast to the upper end of the sleeve 21 and has an inturned flange 32 at the upper end thereof which overlies but is spaced above the upper end of the sleeve 21. An outstanding collar 33 on the thimble 27 is confined between the flange 32 and the upper end of the sleeve 21 and the engagement of this collar either with the flange or the upper end of the sleeve limits movement of the thimble on the polygonal portion 19.

While the foregoing is a preferred manner of mounting and imparting movement to the agitator provided in the tub 7, it is to be understood that the agitator could be mounted in the tub other than in the manner shown and described and likewise movement might be otherwise imparted to the agitator without departing from the purview of my invention.

A plurality of upstanding fins or blades 34 are provided on the agitator 20. In the present instance I have shown four such fins and the inner ends of the flat upper edges of these fins merge into the periphery of the sleeve 21 near the inception of the outward flare thereof, while the vertical outer edges of these fins are spaced slightly inwardly from alignment with the rim of the outwardly flared portion of the agitator. The bottom and inner vertical edges of these fins merge into the outwardly flared portion of the agitator. When an oscillatory movement is imparted to the agitator 20, the fins 34 will move through a liquid in the tub 7 and so agitate the liquid that a cleansing movement will be imparted thereto.

Ears 35 are provided on the periphery of the sleeve 21 near the upper end thereof and these ears preferably extend outwardly from the sleeve in alignment with the upstanding fins 34. When the ears 35 are immersed in liquid in the tub 7 and are permitted to move through this liquid they impart additional agitation to the liquid and enhance the effectiveness of the cleansing movement imparted to the liquid. However, as will be explained hereinafter, the ears 35 are sometimes enclosed and in these instances the

fins 34 are relied upon to impart cleansing movement to the liquid in the tub 7.

It is advantageous to wash light and delicate articles of clothing and the like separately from heavier articles to avoid tearing or otherwise damaging the lighter and more delicate articles. This may be accomplished by washing these lighter and more delicate articles in a separate compartment. Such a separate compartment is provided in the embodiment of the invention illustrated by the substantially bowl-shaped member 36 which has an upstanding sleeve 37 at the center thereof. The sleeve 37 is adapted to embrace the periphery of the sleeve 21 and pockets 38 formed in the member open into this sleeve and receive the ears 35, the upper ends of the ears 35 engaging the tops of the pockets 38 to support the member 36 in the tub. Preferably the pockets 38 are of such a width that they neatly embrace the sides of the ears 35 and prevent relative movement between the member 36 and the sleeve 21 of the agitator 20. The seating of the ears in the pockets, however, insures movement of the member 36 with the agitator 20. The pockets extend into the compartment provided by the member 36 and constitute ribs which serve to agitate liquid in the compartment. Preferably the compartment provided by the member 36 is in communication with the rest of the tub and this may be attained by providing openings 39 in the member 36 so that the liquid in the tub may freely flow into the compartment when the member 36 is mounted on the sleeve 21. By providing the openings 39 in the bottom of the member 36 installation of the member 36 on the sleeve 21 is facilitated for as the member is forced down over the sleeve the liquid in the tub 7 freely passes through openings 39 in the bottom of the member 36, and this materially reduces the resistance offered to installation of the member 36. Moreover in this manner the compartment is filled with liquid which reduces the buoyancy of the member and prevents it floating on the liquid in the tub.

While it is desirable to provide the member affording the compartment separate from the rest of the tub with liquid agitating means it is not essential that such means be utilized to connect the member to the agitator. In Figs. 5 and 6 I have shown a member 40 which provides a compartment separate from the rest of the tub and this member has inwardly bent ribs 41 formed therein at spaced intervals about the periphery thereof. These ribs constitute liquid agitating means for the compartment provided by the member 40. The member 40 has an upstanding polygonal tapered sleeve 37' at the center thereof that is otherwise similar to the sleeve 37. The agitator 20' is similar to the agitator 20 and has an outwardly flared lower end 24' and fins 34' but instead of being provided with ears 35, the upper end 42 of the sleeve 21' is of polygonal outline complementary to the polygonal sleeve 37' and this upper end 42 is tapered. Preferably, as shown in Fig. 6, the taper of the upper end 42 constitutes a continuation of the outwardly flared portion 24'. The lower end of the taper is larger than the upper end. The sleeve 37' is similarly tapered so that when it is fitted over the part 42 the tapers cooperate to limit the distance the sleeve 37' may move down the sleeve 21' and this supports the member 40 on the sleeve 21'. The member 40 is provided with openings 39' for the same purpose as and located simi- 75

larly to the openings 39. In other respects the agitator 20' is similar to the agitator 20.

In use, saponified water or other cleansing liquid is introduced into the tub 7 in an amount sufficient to fill the tub up to about the top of the ears 35 or about the upper end of the polygonal portion 42 on the agitator 21'. If no light and delicate articles are to be washed, the means for imparting movement to the shaft 9 are set in operation and the ears 29 are seated in the recesses 28 whereupon the agitator, and particularly the fins 34 and the ears 35, induces a cleansing movement in the liquid to effect thorough cleansing of articles of clothing or the like introduced into the liquid in the tub 7. In the form of the invention shown in Fig. 1, both the fins 34 and the ears 35 agitate the liquid to impart the cleansing movement thereto, while in the form of the invention shown in Fig. 5 the fins 34' are relied upon to impart cleansing movement to the liquid.

When light and delicate articles are to be washed simultaneously with other articles of clothing and there is likelihood that the lighter and delicate articles might be torn or damaged if washed with the other articles, these light and delicate articles may be washed in the compartment separate from the other articles. In the form of the invention shown in Fig. 1 the member 36 may be mounted on the sleeve 21 of the agitator 20 prior to the time any liquid is introduced into the tub 7 and as liquid is introduced into the tub 7 it will flow through the openings 39 and fill the member 36 to the same level as that to which the tub 7 is filled. When, however, the tub 7 has been previously filled with liquid the member 36 will be forced down onto the sleeve 21 and the liquid will course through the openings 39. When the member 36 is so installed on the sleeve 21 the ears 35 are embraced in the pockets 37 and in this instance the fins 34 are relied upon to impart cleansing movement to the liquid in the tub when the agitator is set in operation. When the agitator is set in operation the portions providing the pockets 37 impart cleansing movement to the liquid in the member 36 and this movement effects thorough cleansing of articles of clothing in the compartment provided by the member 36 without damage to these articles. Similarly, when the member 40 is installed on the sleeve 21' in either of the ways in which the member 36 is installed on the sleeve 21 and the agitator is set in operation the ribs 41 impart cleansing movement to liquid in the compartment provided by the member 40 to effect cleansing of articles in this compartment without damage thereto.

While I have illustrated and described a preferred form of my invention it is to be understood that this is capable of variation and modification and I therefore do not wish to be limited to the precise details set forth but desire to avail myself of such changes and alterations as fall within the purview of the following claims.

I claim:

1. In a washing machine, a tub, an agitator extending into the tub from the bottom thereof and having agitating means thereon at the lower end thereof for imparting cleansing movement to liquid in the tub, said tub being filled well above said agitating means, supporting means on said agitator near the upper end thereof, a member providing a compartment and having portions thereon adapted to embrace said supporting

means to connect said member to said agitator, said member being spaced from and independent of the agitating means and having openings therein through which liquid in the tub may pass into the compartment whereby certain articles of clothing or the like may be washed in the liquid in the compartment out of contact with other articles of clothing or the like being washed in the liquid in the tub, and means on said member for imparting cleansing movement to the liquid in the compartment.

2. In a washing machine, a tub, an agitator extending into the tub from the bottom thereof and having agitating means thereon at the lower end thereof for imparting cleansing movement to liquid in the tub, said tub being filled well above said agitating means, supporting means on said agitator near the upper end thereof, a member providing a compartment and having formed portions thereon extending into said compartment, said formed portions providing pockets adapted to embrace said supporting means to detachably connect said member to said agitator, said member being spaced from and independent of the agitating means and having openings therein through which liquid in the tub may pass into the compartment whereby certain articles of clothing or the like may be washed in the liquid in the compartment out of contact with other articles of clothing or the like being washed in the liquid in the tub, the formed portions projecting into said compartment providing cleansing movement to the liquid in the compartment to facilitate washing of articles of clothing in the compartment.

3. In a washing machine, a tub, an agitator in said tub, agitating means on said agitator at the lower end thereof, supporting means on said agitator near the upper end thereof, a member providing a compartment in said tub, and means on said member adapted to embrace said supporting means on said agitator to detachably connect said member to said agitator and support said member on the agitator in spaced relation with the agitating means, said agitating means adapted to impart a cleansing movement to a liquid in the tub and said embracing means adapted to impart a cleansing movement to a liquid in said member whereby articles of clothing or the like in said member are cleansed separately from articles of clothing or the like in said tub.

4. In a washing machine, a tub, an agitator in said tub, agitating means on said agitator at the lower end thereof, supporting means on said agitator near the upper end thereof, a member providing a compartment in said tub, said member having pockets therein adapted to receive said supporting means on said agitator to detachably connect said member to said agitator and support said member on the agitator in spaced relation with said agitating means, and means associated with said pockets and extending inwardly of said member to provide agitating means in said member, said agitating means at the lower end of the agitator adapted to impart a cleansing movement to a liquid in the tub and said agitating means in the member adapted to impart a cleansing movement to a liquid in said member whereby articles of clothing or the like in said member are cleansed separately from articles or the like in said tub.

ARTHUR H. LABISKY.
